(57) **CLAIM**

The ornamental design for a faucet-mounted water treatment device, as shown and described.

DESCRIPTION

FIG. 1 is a perspective view of a first embodiment of our new design for a faucet-mounted water treatment device;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof;

FIG. 7 is a bottom plan view thereof;

FIG. 8 is a perspective view of a second embodiment of our new design for a faucet-mounted water treatment device;

FIG. 9 is a front elevational view thereof;

FIG. 10 is a rear elevational view thereof;

FIG. 11 is a left side elevational view thereof;

FIG. 12 is a right side elevational view thereof;

FIG. 13 is a top plan view thereof; and,

FIG. 14 is a bottom plan view thereof.

UNITED STATES PATENT AND TRADEMARK OFFICE
CERTIFICATE OF CORRECTION

PATENT NO. : Des 438,592 S

Page 1 of 1

DATED : March 6, 2001

INVENTOR(S) : Johannes Nikolai Gaston, Douglas James VanOrnum

It is certified that error appears in the above-identified patent and that said Letters Patent is hereby corrected as shown below:

Title page.

Item [75] Inventors: "Douglas James Vanormum" should read
-- Douglas James VanOrnum --

Signed and Sealed this
